US00D807527S

(12) **United States Design Patent** (10) Patent No.: **US D807,527 S**
(45) Date of Patent: ** *Jan. 9, 2018

(54) **RAIL**(71) Applicant: **CPG International LLC**, Scranton, PA (US)(72) Inventors: **Paul M. Bizzarri**, Mason, OH (US); **Chip Herr**, Columbus, OH (US); **John M. Previte**, Dublin, OH (US); **Kevin T. Burt**, Columbus, OH (US); **William G. Taylor**, Columbus, OH (US); **Matthew T. Fenneman**, Gahanna, OH (US); **Jeffrey R. Burr**, Loveland, OH (US); **Timothy C. Rothwell**, Dublin, OH (US)

(*) Notice: This patent is subject to a terminal disclaimer.

(**) Term: **15 Years**(21) Appl. No.: **29/561,819**(22) Filed: **Apr. 20, 2016**

Primary Examiner — Susan Bennett Hattan

Assistant Examiner — Leanne Was-Englehart

(74) *Attorney, Agent, or Firm* — Standley Law Group
LLP

(57) **CLAIM**

The ornamental design for a rail, as shown and described.

DESCRIPTION

The Applicant would also like to let the Examiner know that the following related applications are also currently pending:
29/520,836, filed on Mar. 18, 2015, claims the benefit of 13/461,496

29/520,840, filed on Mar. 18, 2015, claims the benefit of 13/461,496

29/520,842, filed on Mar. 18, 2015, claims the benefit of 13/461,496

29/520,846, filed on Mar. 18, 2015, claims the benefit of 13/461,496

29/520,849, filed on Mar. 18, 2015, claims the benefit of 13/461,496

14/712,373, filed on May 14, 2015, claims the benefit of 13/461,496

14/712,412, filed on May 14, 2015, claims the benefit of 13/461,496

29/532,103, filed on Jul. 1, 2015, claims the benefit of 13/461,496.

FIG. 1 is an elevation view of a rail; and,

FIG. 2 is a perspective view of the rail of FIG. 1.

The broken lines in the figures indicate environment that forms no part of the claimed design.
